United States Patent Office.

HENRY S. SHISLER, OF MANHEIM TOWNSHIP, PENNSYLVANIA.

Letters Patent No. 81,017, dated August 11, 1868.

IMPROVEMENT IN FARM-GATES.

The Schedule referred to in these Letters Patent and making part of the same.

TO ALL WHOM IT MAY CONCERN:

Be it known that I, HENRY S. SHISLER, of Manheim township, in the county of Lancaster, and State of Pennsylvania, have invented a new Arrangement for Operating Farm-Gates; and I do hereby declare that the following is a full and exact description thereof, reference being had to the accompanying drawings, making a part of this specification, in which—

Figure 1 represents the gate in position, with my improvements in place.

Figure 2 is a separate illustration of my sliding clamp and wedge to support the rails or gate when hoisted up in front.

Figure 3 illustrates the combined drop and connection with the sliding latch.

Figure 4, the slotted post for the adjustable latch-catch.

The nature of my invention consists in providing a drop-bar, so connected with the latch, that by raising it up it draws the bolt or latch back, and will drop by its own weight to push the bolt out again, as also the loop for slipping over a wedge-piece connected with the diagonal rail.

To enable others skilled in the art to make and use my invention, I will proceed to describe its construction and operation.

The gate itself is of the ordinary kind, swinging freely on its hinges to the right and left. The front and hind vertical posts A A'', or rails of the gate, are double, with the rails 1, 2, 3, 4, and 5 between them, held by pivot-bolts, upon which they move. The central upright of the gate, A', is single, on which the rails are secured by pivot-bolts. This constitutes the gate, in which there is no novelty.

To the rear upright, A'', between the first and second rail, I fasten, by a pivot-bolt, the drop-bar B. This slides, and is confined by a loop on the central upright, A'. Near the forward end (which may be made heavier by adding a weight of some kind, if necessary,) I affix by a pivot a connecting-lever, C, with the sliding bolt D. This bolt rests on the top of the third rail. The cord for operating the bolt is double, and fastened by an eye, or otherwise, to the forward end of the drop-bar, and carried up over a pulley or through a loop on the upper rail, one end of the cord carried to the right through an eye or pulley on N to the gallows-post and arm O on each side of the gate, to the desired distance. A pull on the rope will withdraw the latch and open the gate. A similar pull on the opposite end of the rope will again close the gate, or pull it open in the opposite direction, without the use of a vertical lever and spring, as the horizontal (or nearly so) drop-bar B falls of its own gravity, and pushes the bolt forward so as to latch the gate. The latch-catch L is made adjustable in a slot of the post K, so that when it is desirable to raise the gate in front, to allow small stock, such as hogs and sheep, to pass in and out, or to raise it from snow or other obstruction, the catch L can be pushed up to adapt it for the raised gate.

The diagonal cross-piece F is held in a pivot on the lower rail 5, and connected above by a loop with a wedge-shaped piece, G, sliding under the upper rail 1. When the gate is elevated in front, it draws the bolt or wedge G back; a movable clamp, E, around the upper rail and wedge, is pushed back as a follower, in order to clamp the wedge, and sustain the gate in that position. This mode of clamping allows a wide range of adjustment without weakening the top rail with holes or notches.

I am aware that a gate is patented, No. 73,016, in which an upright lever is claimed, with a spring, clip, and latch, when arranged, combined, and operated by rope and pulley, as specified; also, a diagonal rail, adjusted by a pin in the upper rail of the gate, in which holes are made to receive the pin. This arrangement and combination I disclaim.

What I claim as my invention, and desire to secure by Letters Patent, is—

The self-acting drop-bar B, connecting lever C to the latch-bolt D, in combination with the sliding wedge-bar G operated by the diagonal bar F, and the movable clamp E, all arranged and operating in the manner and for the purpose specified.

HENRY S. SHISLER.
